(No Model.)

J. W. McKNIGHT.
PROTECTOR FOR INCANDESCENT BURNERS.

No. 606,226.

Patented June 28, 1898.

UNITED STATES PATENT OFFICE.

JOHN WESLEY MCKNIGHT, OF PHILADELPHIA, PENNSYLVANIA, ASSIGNOR
OF THREE-FOURTHS TO PHILIP LEWIN, JULIUS L. LEWIN, MARCUS
LEWIN, AND MAURICE S. LEWIN, OF SAME PLACE.

PROTECTOR FOR INCANDESCENT BURNERS.

SPECIFICATION forming part of Letters Patent No. 606,226, dated June 28, 1898.

Application filed June 15, 1897. Serial No. 640,824. (No model.)

To all whom it may concern:

Be it known that I, JOHN WESLEY MCKNIGHT, a citizen of the United States, residing at Philadelphia, in the county of Philadelphia and State of Pennsylvania, have invented certain new and useful Improvements in Protectors for Incandescent Lights; and I do hereby declare the following to be a full, clear, and exact description of the invention, so such as will enable others skilled in the art to which it appertains to make and use the same.

This invention relates to protectors or guards, and particularly to protectors for the chimneys and mantles of incandescent burners wherein an incandescent mantle is employed; and the objects of the invention are to provide a protector of this character adapted to fit chimneys or globes of different sizes and to prevent flies or other insects from entering the chimney and injuring the mantle or from alighting upon the chimney and occasioning an accumulation of matter thereon, which not only dirties the chimney, but dampens the same, so that when the burner is lighted the chimney will break.

A further object of the invention is to prevent the pieces of glass from falling upon the floor or other objects if the chimney should break, and also to provide a protector which can be secured in position without jarring the mantle; and with these and other objects in view the invention consists in the construction and arrangement of parts hereinafter more fully described in the specification and illustrated in the accompanying drawings, in which—

Figure 1 is a view of a burner and chimney provided with my improved protector. Fig. 2 is a side elevation of a burner and chimney, showing my improved protector in position thereon, partly broken away. Fig. 3 is a central longitudinal section of the construction shown in Fig. 2. Fig. 4 is a transverse section on line 4 4 of Fig. 2, looking in the direction of the arrow X. Fig. 5 is a transverse section on line 5 5 of Fig. 2, looking in the direction of the arrow Y; and Fig. 6 is a sectional view of the base portion.

Similar characters of reference designate like parts throughout the several views.

Referring to the drawings, the numeral 1 indicates a portion of an ordinary gas-bracket provided with a gas-supply pipe, and on this bracket 1 is mounted in the usual manner a burner 2, adapted to be used in connection with an incandescent mantle, and this burner may be of the usual construction, for it forms no part of this invention.

My improved protector consists of several parts, which are made detachable from the burner and chimney and from each other in order that when one part becomes unfit for use a new part may be substituted without renewing the entire protector, as will be hereinafter more fully explained.

The lower or base portion 3 of the protector is constructed of wire-mesh or other suitable material, preferably semispherical in form, to fit the convex base or lower portion of the burner, and the rim or edge of the base portion 3 is bound or edged with a strip 4, of metal or other material, as shown in Fig. 6, to retain the wires in position and to give rigidity thereto, and in the bottom of the base portion 3 is formed an opening 5, made of any suitable size and shape to fit the burner-tube, upon which it is secured, and the edge of the base portion around the opening 5 is provided with a metallic or other binding 6 of suitable character.

It will be understood that the base portion 3 may be constructed in a different form or configuration from that herein shown and described, so that it will fit or inclose the lower portion of any incandescent burner to which it may be desirable to apply the same.

The main or body portion 6' of the protector is cylindrical in form, and the free edges 7 and 8 are bound or faced with a metallic or other strip 9, and the upper and lower edges are also similarly bound or faced, and at one end or extremity of the bindings or facings 10 and 11 are secured pins or studs 12, adapted to enter openings 13 in the other ends of the bindings or facings 10 and 11, and by means of these openings the diameter of the main portion 6 may be increased or dimin-

ished, according to the size of the chimney with which it is desired to be used.

The top or cap portion 14 is composed of a cylindrical part 15, the sides or edges 16 of which are bound or faced with a metallic or other strip, as shown in Fig. 2, and these strips are connected by means of wire loops or staples 17, which pass through openings in the strips, and the ends of the loops are bent 10 or clenched upon the inside of the strips in any suitable manner, and the upper edge of the top portion 14 is bound or faced with a metallic or other strip 18, and, if preferred, the lower edge may be so bound or faced, but 15 it is not so shown in the drawings.

Upon the upper bound or faced edge 18 is removably secured a metallic band or rim 19, having an inwardly-directed annular flange 20, and within this band and resting upon 20 said flange is detachably held a circular top 21, preferably concavo-convex in cross-section, and this top is constructed of wire-mesh of coarser texture than the other parts of the protector; but, if desired, the same may be 25 constructed of any other suitable material.

If found desirable in practice, the top or cap portion may be hinged or otherwise connected to the main portion 6, and by making the base portion 3 in substantially the manner shown and described the same may be 30 readily secured below the base of a burner, and thereby flies or other insects will be prevented from crawling up into the chimney and mantle and injuring them, and by the 35 peculiar construction of the main portion 6 the same may be easily adjusted or removed without jarring or injuring the mantle, and the top or cap portion 14 may also be readily secured in position or removed, and when the 40 top 21 is burned out or injured a new one can easily be inserted within the band 20, and thus each part of the protector can be removed or renewed independently of the other parts.

The top or cap portion 14 also serves to keep 45 flies and other insects from crawling into the top of the chimney and injuring the chimney and mantle, and the main portion 6 protects the exterior of the chimney from these insects 50 and from the injuries which they cause.

I do not desire to confine myself to the construction and arrangement of parts herein shown and described, and I therefore reserve the right to make all such changes in and 55 modifications of the same as come within the scope of my invention.

Having accurately described my invention, what I claim as new, and desire to secure by Letters Patent, is—

1. A removable protector of the character described, consisting of independent portions, a cup-shaped base portion, an adjustable main portion, and a top or cap portion.

2. A protector of the character described, 65 consisting of a cup-shaped base portion, an

adjustable cylindrical main portion, and a cylindrical top or cap portion, and a removable top for the cap portion, said parts being removable from the burner and chimney and independent of each other.

3. A protector of the character described 70 consisting of a cup-shaped base portion having an opening in the bottom thereof for the admission of the burner-tube, an adjustable main portion and a cylindrical top portion.

4. A protector of the character described 75 consisting of a cup-shaped base portion having an opening in the bottom thereof, the edges of said opening and of the base portion being provided with a metallic binding, an adjustable main portion and a top portion.

5. A protector of the character described 80 consisting of a cup-shaped base portion having an opening in the bottom thereof for the admission of the burner-tube, the edges of 85 said opening and of the base portion having a rigid binding, a cylindrical main portion provided with rigidly-bound edges, means for adjusting the same and a top portion.

6. A protector of the character described 90 consisting of a cup-shaped base portion having an opening in the bottom thereof for the burner-tube, the edges of said opening and of the base portion having a rigid binding, a cylindrical main portion provided with rigidly-bound edges, means for adjusting the same 95 and a cylindrical top portion having reinforced edges.

7. A protector of the character described 100 consisting of a cup-shaped base portion having an opening in the bottom thereof for the burner-tube, the edges of said opening and of the base portion having a rigid binding, a cylindrical main portion provided with rigidly-bound edges and with means for adjusting 105 the same, a cylindrical top portion having reinforced edges, a removable flanged band upon the top portion and a wire disk within the band.

8. A protector of the character described 110 consisting of a cup-shaped base portion having an opening therein for the admission of the burner-tube, the edges of said opening and of the base portion having a rigid binding, a cylindrical main portion provided with 115 rigidly-bound edges and with means for adjusting the same, a cylindrical top portion having reinforced edges, a removable flanged band upon the top portion, and a concavo-convex wire disk removably secured within 120 said band, all of said parts being removable from the burner and chimney and independent of each other.

In testimony whereof I affix my signature in presence of two witnesses.

JOHN WESLEY MCKNIGHT.

Witnesses:

EDWIN N. VOGEL,
CHAS. DOUGLAS.
